UNITED STATES PATENT OFFICE

BELVIN T. WILLISTON, OF SOMERVILLE, MASSACHUSETTS, ASSIGNOR TO CONSOLIDATED ASHCROFT HANCOCK COMPANY, OF NEW YORK, N. Y., A CORPORATION OF DELAWARE

EXHAUST NOZZLE

Application filed January 19, 1929. Serial No. 333,621.

This invention pertains to draft regulators for furnaces, and more particularly to exhaust nozzles, and while of more general utility, the invention is herein disclosed as applied to a locomotive wherein such nozzles are commonly employed. When thus used, the exhaust nozzle is usually arranged directly below, but spaced from, the lower end of the smoke stack, and is adapted to deliver exhaust steam upwardly into the stack, thus entraining with it the smoke and furnace gases and ejecting them through the stack, at the same time creating a draft through the furnace. For best and most economical operations of a locomotive, an exhaust pressure of about four pounds is usually maintained, and the present invention provides for the efficient use of exhaust steam at this relatively low pressure to secure a powerful draft. With this object in view, instead of delivering the steam as a single solid jet through a plain nozzle, I so divide the jet as to provide a greatly increased area of contact between the flowing steam and the surrounding furnace gases, and lead a portion of the furnace gas inwardly toward the center of the nozzle through appropriately shaped channels, thereby greatly increasing the ejector action of the steam.

While I am aware that attempts have been made to increase the ejector action by providing obstructions in the nozzle orifice so as to break up the continuity of the flowing steam jet, such arrangements are more or less uncertain in action and do not substantially increase the exposed surface of the steam jet for frictional engagement with the furnace gas.

In the accompanying drawings I have illustrated one embodiment of the present invention by way of example, and in the drawings:

Fig. 1 is a fragmentary diagrammatic vertical section of the forward portion of a locomotive showing my improved exhaust nozzle in its relation to the stack;

Fig. 2 is a plan view to larger scale of my improved exhaust nozzle;

Fig. 3 is a vertical section substantially on the line 3—3 of Fig. 2;

Fig. 4 is a diagrammatic view, generally similar to Fig. 1 but to smaller scale, illustrating the use of my exhaust nozzle with a stack of different type; and

Fig. 5 is a fragmentary section substantially on the line 5—5 of Fig. 2.

Referring to the drawings the numeral 1 designates the shell of the smoke box of a locomotive, such shell being provided with the usual internal deflector plates and screens defining the chamber 2 into which the lower end of the stack 3 opens. Usually, as illustrated, the lower end of the stack is flared outwardly and downwardly so as to increase the ejector action of the steam jet.

The usual exhaust pipe 5 extends upwardly into the lower part of chamber 2, substantially in axial alignment with the stack 3, and is shown as provided with the usual radial flange 6 forming a seat for the reception of the exhaust nozzle 7.

Referring more particularly to Figs. 2, 3 and 5, my improved nozzle comprises an annular body portion 8 adapted to fit snugly onto the upper end of the exhaust pipe 5, and preferably having a radial flange 9 provided with suitable openings to receive bolts for attaching it to the flange 6 of the pipe 5. The exhaust nozzle has a steam admission opening 10 registering with the bore of the exhaust pipe 5, and above the flange 9 the nozzle comprises a substantially cylindrical portion or shell 11. This shell is provided with a plurality of circumferentially spaced openings 12, here shown as vertically elongate slots disposed substantially ninety degrees apart and below the upper edge of the shell.

A plurality of conduits 13 lead inwardly from the shell 11 toward the center of the nozzle. These conduits are preferably in the form of upwardly open substantial U-shaped webs whose side walls and bottoms are preferably integral with the shell 11. These channel-like webs preferably merge at the center of the nozzle, as indicated at 16, and the bottoms 15 of the web members slope upwardly from the lower ends of the slots 12 toward the center of the nozzle so that the guide channels 14 are deepest adjacent to the

shell 11 and gradually decrease in depth toward the center so as to supply substantially equal quantities of gases to portions of steam jets served by these passages and also to provide for compactly arranging jets of maximum capacity for efficient operation. Each channel 14 registers with one of the openings 12, and the U-shaped web-like conduits 13 divide the space within the shell 11 so as to form a plurality of independent segmental steam-delivery passages 17. Adjacent passages are spaced apart a distance equal to the width of the intervening conduit 13 so that the emerging jets of steam are entirely independent where they leave the nozzle, each jet presenting a peripheral surface comprising an arcuate outer surface, and substantially straight intersecting inner surfaces. The channels 14 provide free access for the furnace gases to enter radially between the steam jets so as to contact with the inner surfaces of the several jets, and by the division of the steam into a plurality of separated jets, as above described, a much larger surface than usual is provided for frictional engagement of the steam with the gases: this greatly increases the ejector effect so that with a given quantity of steam at a given pressure it is possible to obtain a much more powerful draft than when employing a plain nozzle delivering all of the steam in the form of a single jet.

In Fig. 4 I have shown an improved nozzle applied to a stack of somewhat different form. In this figure the shell of the smoke box is indicated at 1^a, the stack at 3^a, and the chamber, into which the stack opens, at 2^a. In this case the stack proper is relatively short, but is provided with a series of annular truncated, conical skirt members 18 coaxial with the stack proper and spaced apart vertically and adapted to increase the ejector effect. The exhaust pipe 5^a is provided with my improved nozzle 7, and when this combination is employed an even more powerful draft is obtained than in the arrangement shown in Fig. 1, since the increased volume of fluid, resulting from the use of this nozzle, when delivered into the lowermost skirt 18 produces an unusually high velocity which in turn reacts to entrain more gas, thus progressively adding to the ejector effect.

While I have shown the gas conduits 13 of the nozzle as consisting of integral channel-like webs, I contemplate that these conduits may be formed as independent elements secured in any desired manner within the body of the nozzle proper; and while I have shown these conduits as of channel form, open towards the delivery end of the nozzle, I contemplate that other forms of conduit may be employed, provided they furnish a substantial passage for the delivery of the furnace gases into the spaces between the several jets.

Moreover, while I have here shown the nozzle

as provided with means defining four independent steam jets, I do not wish to limit the invention to the precise number of jets employed, nor in the broader aspects of the invention to the complete separation of the several jets, since desirable results may be obtained with a greater or lesser number of jets, and with somewhat less than the maximum possible inner surfaces of the jets exposed to the gas. Moreover the proportions of the parts of the nozzles may be varied as circumstances may warrant, and I regard all such changes as above suggested as falling within the spirit of the invention.

I claim:

1. An exhaust nozzle comprising an annular body portion and means providing passages for conducting gases from the rim of the body to its axis, said conducting means defining a plurality of spaced upwardly directed steam jets so that the steam delivered by the nozzle exposes a surface substantially greater than that of a solid cylindrical jet for entrainment of the gases delivered by said conducting means, said gas passages being convergent inwardly toward the center of the nozzle for supplying gases to issuing steam approximately in proportion to the entraining capacity of adjacent bodies of such issuing steam.

2. An exhaust nozzle comprising an annular body portion and a plurality of channel members extending inwardly from the rim of the body to its center, said channel members defining a plurality of steam delivering passages adapted to deliver spaced independent steam jets, the channel members providing passages for conducting gases inwardly from outside of the body portion and delivering said gases in the spaces between the steam jets, the gas passages converging inwardly toward the center approximately in proportion to the entraining area of the respective jets, whereby substantially equal quantities of gases may be supplied to all portions of all of the jets.

3. An exhaust nozzle comprising a body portion having an attaching flange and a cylindrical wall provided with circumferentially spaced openings, and gas conductors of channel-section leading inwardly from the respective openings and merging at the center, said channel sections being open toward the discharge end of the nozzle and defining a plurality of segmental steam delivery passages spaced apart by the interposed conductors, the sectional flow area of the gas conductors decreasing toward the center so that substantially equal quantities of gases may be supplied to all sides of the jets and jets of maximum capacity may be compactly arranged for efficient operation.

4. An exhaust nozzle of the class described, comprising an attaching flange and a cylindrical wall extending upwardly therefrom,

circumferentially spaced openings disposed between the flange and the upper edge of the cylindrical wall, radially disposed channel members registering at their outer ends with said openings and communicating with each other at the center of the nozzle, the outer side walls of the channel members cooperating with the cylindrical wall to define jets for exhaust steam, the channel members being open at the top throughout their length for supplying gases to adjacent jets, the bottoms of the channel members being inclined upwardly toward the center of the nozzle to provide passages diminishing in sectional flow area toward the center of the nozzle for supplying substantially equal quantities of gases to the portions of the jets served by said passages.

5. The combination as set forth in claim 4, wherein the channel members are of like dimensions and are symmetrically disposed to define jets of like size.

Signed by me at Boston, Massachusetts, this 18th day of January, 1929.

BELVIN T. WILLISTON.
